LIGHTNING ARRESTER

Ainslie T. Carter, Coldwater, N. Y., assignor to
General Railway Signal Company, Rochester,
N. Y.

Application September 21, 1928, Serial No. 307,471

7 Claims. (Cl. 175—30)

This invention relates in general to lightning arresters, and has more particular reference to an arrester of the vacuum tube type having an air spark gap in multiple with the tube.

5 In lightning arresters of the gas tube type, there is always the danger of the tube failing and hence of losing proper protection. In order to avoid this danger, it is usual to provide, in multiple with the gas tube, a usual spark gap 10 type of arrester having a break down voltage somewhat greater than the break down voltage of the gas tube so that the gas tube normally functions to ground excessive currents but in the event of its failure the air spark gap will 15 afford proper protection.

It is one object of this invention to provide a simple and economical means of providing an air spark gap which will be uniform and predetermined in length in all arresters produced.

20 Further objects, purposes and characteristic features of the present invention will appear as the description progresses, reference being had to the accompanying drawing showing, solely by way of example, and not in any manner 25 whatsoever in a limiting sense, one form which the invention can assume. In the drawing:—

Fig. 1 is a side elevation of one form of the invention, with parts shown in section.

Fig. 2 is an axial sectional view through a 30 lightning arrester cartridge constructed in accordance with this invention.

Fig. 3 is a diagrammatic view of the invention.

Referring now to the drawing, the lightning arrester comprises an insulating base 1 of porcelain or the like, to which are connected binding posts 2 and 2¹. Connected to the base 1 by the binding posts 2¹, are receiving clips 3 formed of electrically conducting springy material spaced so as to readily receive an arrester cartridge C, by means of the projecting conducting sleeves 4 on the cartridge.

The cartridge C comprises a hollow cylindrical conducting shell 5, formed preferably of metal, with end discs 6 of porcelain or other 45 non-conducting material, over which the ends of the cylinder 5 are crimped, as shown at 5¹, the ends 5¹ of cylinder 5 extending only part way across the outer face of each disc 6. A conducting stud 7 passes through each disc 6 50 and projects outwardly beyond the outer face of its disc so as to receive a washer 8 of non-conducting material, accurately formed in its various dimensions so as to snugly fit over the stud 7, and bearing flat against the crimped or bend- 55 ed over portion 5¹ of cylinder 5. A second wash-

er 9 of conducting material is likewise received on each of the studs 7 so as to bear flat against the corresponding washers 8. Holding the washers 8 and 9 in place against each other and against the crimped over portion 5¹ of cylinder 5, are the sleeves 4 which are held in place on studs 7 by means of solder or the like 4¹.

Within the cartridge C is a sealed glass tube 10, having lead-in wires 11 sealed in the ends of the tube 10 and in the solder 4¹ and connected within the tube 10 to spaced electrodes 12. The tube is filled with neon gas, or other usual or suitable gas, under subatmospheric pressure, in a manner usual in such devices.

Diagrammatically shown at 13 is a relay connected up as shown in Figs. 1 and 3 so as to be energized through a circuit including one terminal B of a source of energy, binding post 2 and adjacent post 2¹, the winding of relay 13, and the other terminal C of the source. Flow 20 from the terminal B of the source of energy, also can take place, if the voltage is sufficiently high, through a parallel path to ground 14, this parallel path including, in parallel, one circuit including the gap between the electrodes 12, and a second circuit including the two air gaps between the conducting washers 9 and the ends 25 5¹ of cylinders 5, in series.

The structure forming the two air gaps in series between the washers 9, and the crimped over ends 5¹ of cylinder 5, insures accurately formed air gaps of invariable and predetermined length so long as the washer 8 be accurately dimensioned. It is a very simple matter to form these washers 8 of predetermined and uniform 30 dimensions, and hence a simple and economical construction has been afforded which insures uniform air gaps of predetermined dimensions.

It is most important that these air gaps be formed accurately, and of the desired predetermined dimensions, since if they are too short the break down voltage across the two air gaps in series may be less than that across the electrodes 12, with the result that air gaps and not the gas tube, normally functions to care for 40 overloads. On the other hand, if the two air gaps in series be too long, the break down voltage may be so great that even on failure of the gas tube, no current will flow to ground upon excessive voltage, and hence no secondary protection 45 will be afforded the translating device 13, upon failure of the tube 10.

The above rather specific description of one form of the present invention, is given solely by way of illustration, and is not intended, in 50 55

any manner whatsoever, in a limiting sense. Obviously, the invention can assume many different physical forms, and is susceptible of numerous modifications, and all such forms and modifications are intended to be included in this application, as come within the scope of the appended claims.

Having described my invention, I now claim:—

1. In a lightning arrester, an arrester unit, said unit comprising, a hollow open ended shell of conducting material, an end piece of insulating material forming each end of said shell with said conducting material crimped over the outer end of each end piece, a conducting stud spaced from said crimped ends and passing through each end piece and projecting beyond the outer face of each end piece, an accurately formed insulating washer on each stud and bearing flat against said crimped over parts of said shell, and a conducting washer on each stud and bearing flat against said insulating washer, whereby to form an invariable air gap of predetermined size between said conducting shell and said conducting washers.
2. In a lightning arrester, in combination, an open ended cylindrical metallic shell, a non-conducting disc in each end of said shell, a conducting stud projecting out from each disc, each end of said shell being crimped over the outer face of each disc and out of contact with said studs, an accurately formed insulating washer on each stud and bearing flat against the crimped over parts of said shell, and a washer of conducting material on each stud and bearing against each insulating washer.
3. In a lightning arrester, in combination, an open ended cylindrical metallic shell, a non-conducting disc in each end of said shell, a conducting stud projecting out from each disc, each end of said shell being crimped over the outer face of each disc and out of contact with said studs, an accurately formed insulating washer on each stud and bearing flat against the crimped over parts of said shell, a washer of conducting material on each stud and bearing against each insulating washer, a sleeve passing over each stud and bearing against said washers

to hold them in contact with each other and said shell, and solder connecting said sleeves and studs.

4. In a lightning arrester, in combination an open ended cylindrical metallic shell, a non-conducting disc in each end of said shell, a conducting stud projecting out from each disc, each end of said shell being crimped over the outer face of each disc and out of contact with said studs, an accurately formed insulating washer of predetermined dimensions on each stud and bearing flat against the crimped over parts of said shell, a washer of conducting material on each stud and bearing against each insulating washer, a sleeve passing over each stud and bearing against said washers to hold them in contact with each other and with said shell, solder connecting said sleeves and studs, lead-in wires passing from said solder and through said studs and into said shell, and a rare gas tube lightning arrester within said shell and connected to said wires.

5. In a lightning arrester, in combination, an open ended metallic shell, a non-conducting head in each end of the shell, a conducting stud projecting out from each head, a washer of conducting material on each stud, and an insulating washer on each stud and electrically insulating each conducting washer from the shell.

6. A lightning arrester of the cartridge type comprising a metal shell, and spark gap elements each consisting of a current conducting element held spaced from an end of the shell by a suitable insulator inserted therebetween whereby the shell serves to interconnect the elements through gaps determined by the insulators, in series relation.

7. A lightning arrester of the cartridge type including, a shell, insulators carried at each end of the shell, spark gap elements on each of said insulators, each including an end of the shell, a conducting washer, and an insulating washer of a desired thickness separating the conducting washer from the end of the shell, said shell thus serving to interconnect said spark gap elements on said insulators in series.

AINSLIE T. CARTER.
